AUGUST SUNDH, OF YONKERS, NEW YORK, ASSIGNOR TO OTIS ELEVATOR COMPANY,
OF JERSEY CITY, NEW JERSEY, A CORPORATION OF NEW JERSEY.

COMBINED FRICTION AND SPUR GEARING FOR TRACTION-ELEVATORS.

1,085,952.

Specification of Letters Patent. Patented Feb. 3, 1914.

Application filed July 6, 1907. Serial No. 382,465.

To all whom it may concern:

Be it known that I, AUGUST SUNDH, a citizen of the United States, residing at Yonkers, in the county of Westchester and State of New York, have invented a new and useful Improvement in Combined Friction and Spur Gearing for Traction-Elevators, of which the following is a specification.

- 10 My invention relates to friction drive elevator apparatus and has for its object to provide efficient noiseless and positive driving gearing for transmitting motion from a motor to a friction drive or traction elevator.
15 In the accompanying sheet of drawing Figure 1 illustrates in front elevation an elevator provided with the improved friction drive apparatus embodied in my invention. Fig. 2 is a side view in part section of the driving apparatus. Fig. 3 is a sectional view of a modification of my invention.

Similar reference characters denote similar parts throughout the various figures.

M designates a hoisting motor secured to the bed 17 and adapted to drive an annular hoisting sheave 6 grooved on its outer periphery. This grooved hoisting sheave lies in a bight of the cable 1 one end of which passes up over an overhead sheave 4 and is 20 connected to an elevator car C, and the other end of which leads up over a similar sheave 3 and is connected to a counterweight 5. Both the sheaves 3 and 4 are mounted in suitable bearings secured to the overhead 25 beams 2. Directly beneath and in close proximity to the annular driving sheave 6 are two grooved rollers 14 and 14' loosely mounted upon shafts 16' and 16'' and carried by stationary bearings 15 and 15' respectively which are secured to the bed 17. The inner periphery of the driving sheave 6 is turned smooth so as to form two friction surfaces 9 and 9' between which is 40 formed an internal spur gear 12. A driving element comprising a spur gear 11 is located midway between two similar friction rollers 10 and 10' which are securely riveted together by rivets 13 and the whole is carried by the motor shaft 7 and rigidly secured thereto by means of a key 8. This driving element engages and co-acts with the inner periphery of the driving sheave 6. It will be seen by an inspection of Fig. 1 50 that the annular driving sheave 6 is pulled upwardly against the driving element car-

ried by the motor shaft with a force substantially equal to the combined weight of the elevator car C and the counterweight 5.

The modified driving means in Fig. 3, while the same in principle as that heretofore described, differs somewhat in construction. In this modification the friction roller 10'' carried by the motor shaft is made in a single piece and is provided with an integral raised portion or collar 18 which fits loosely in a corresponding circular recess 19 in the inner periphery of the driving sheave 6' the object of which is to prevent any relative longitudinal movement between the roller 10'' and the driving sheave 6'. A 70 spur gear 11' is secured to the friction roller 10'' by rivets 13 and co-operates with an internal gear 12' which is integral with the driving sheave 6' and located at one end as shown on the drawing.

Where the driving sheave is very large, in order to facilitate the construction of the internal gear, I sometimes make this gear separately in sections and secure them to the driving sheave afterward, a recess being 80 cast or machined in the driving sheave beforehand to receive them. This method of construction is especially adapted to the arrangement shown in Fig. 2 where the gear is centrally located in the inner periphery 85 of the driving sheave 6.

It has been frequently demonstrated in actual practice that spur gearing when used alone as a means for driving an elevator produces a vibration which is very disagreeable to the passengers carried in the car, at the same time the noise made by gears in mesh is always objectionable. On the other hand friction driving means when used alone is generally unsatisfactory for the 95 reason that it is almost impossible to prevent slipping with subsequent loss of power and undue wear on the friction surfaces.

It should be particularly noted that by reason of the grooved rollers 14, 14' the ring 100 sheave 6 is supported independently of the car and counterweight acting on the cables 1. Although I have shown the cylindrical surface of the rollers 14, 14' grooved so as to engage the cables 1, such rollers may have 105 only surfaces which engage corresponding surfaces on the ring 6 and thus remain entirely out of contact with the cables. However, I prefer the construction shown, but in any event the rollers 14 and 14' not only 110

- support the ring sheave 6 in the position shown to prevent vertical vibration, but also to support such ring sheave to prevent longitudinal movement or vibration thereof.
- 5 This is of importance as it renders the transmission of power more efficient, in that variations of load can only produce a very limited degree of bodily movement of the ring sheave 6. However, the car and counterweight acting upwardly on the leads of the cable 1 extending upwardly from the driving sheave maintain the latter in frictional engagement with the roller 10 with a force proportional to the load. It should also be noted that since the roller 10 engages the ring 6 at its inner periphery there will be a larger area of frictional contact than if such driving roller were connected to the ring sheave 6 at its outer periphery.
- 10 As the friction surfaces of the roller 10 and the ring 6 are cylindrical surfaces parallel with their axes of rotation, and as the friction surfaces and the spur gears have the same pitch diameter, it is apparent that the 15 friction surfaces while in contact hold the gears properly intermeshed, and also that as the gears rotate there need be no slipping between the friction surfaces.

By the use of my invention in frictional driving apparatus, particularly in traction elevators, the driving or transmission of power may be accomplished mostly by the friction rollers, the gears acting as a safety device to prevent slipping between the parts 30 in frictional engagement with each other. Or under some conditions, for instance when the load is great, power may be transmitted to the load positively by the gears, a friction gearing assisting in such transmission 35 and minimizing or preventing noise of the gears due to vibration or back lash.

Obviously those skilled in the art may make various changes in the details and arrangement of parts without departing from the spirit and scope of my invention, and I desire therefore not to be limited to the precise construction herein disclosed.

What I claim as new and desire to have protected by Letters Patent of the United States is:—

1. In frictional driving apparatus, the combination with a friction driving member, of an annulus in frictional engagement with said driving member, mechanism engaging the external surface of said annulus for supporting and holding the same in frictional engagement with said member, and means to prevent slipping between said driving member and said annulus.
- 50 2. The combination with a motor, of a ring sheave, a friction roller or gear connected to the shaft of the motor, and two rollers journaled to fixed supports and holding said ring sheave in frictional engagement with said driving roller and also re-

ducing to a minimum bodily downward movement of said ring sheave, and means to form a positive driving connection between the driving roller and ring sheave.

3. The combination with a motor, of a driving gear connected to the shaft of the motor, an annular member internally geared to and having a positive driving connection with said driving gear, and means in engagement with the periphery of said member and holding said member and driving gear in co-operative relation.

4. The combination with a motor, of a driving element on the motor shaft, an annular member surrounding said element and in frictional engagement therewith, supporting means engaging the periphery of said member, and positively operating means to prevent slipping between the annular member and the driving element.

5. The combination of a motor, a friction gear or roller connected to rotate with the motor shaft, a spur gear connected to also rotate with the motor shaft, an annular ring or sheave surrounding the said roller and spur gear and in frictional engagement with the former, an internal gear carried by the sheave in mesh with said spur gear, and means in rolling engagement with the periphery of the said ring or sheave and forming a support therefor.

6. The combination of a motor, a driving roller or frictional gear connected to rotate with the motor shaft, a ring sheave surrounding the said roller and in frictional engagement therewith, means in rolling contact with the periphery of said sheave and forming a support therefor, and means to prevent slipping between the driving roller and said sheave.

7. The combination with a motor, of a friction driving roller connected to rotate with the motor shaft, a spur gear also connected to rotate with the motor shaft, a ring sheave surrounding the roller and spur gear and in frictional contact with the said roller, supporting means for said sheave in frictional contact with its periphery, and gear teeth secured to the said sheave and in mesh with the spur gear teeth.

8. In combination, a driving element and a driven element, intermediate gearing between said elements consisting of combined friction gears and spur gears, and means to automatically maintain a driving friction between the friction gears.

9. In combination, a driving element and a driven element, intermediate gearing between said elements, consisting of combined friction gears and spur gears, means to automatically maintain a driving friction between the friction gears, and means to automatically increase the friction on the friction gears in proportion to the force required to drive the driven element.

10. The combination of a driving element and a driven element, means for transmitting motion from the driving element to the driven element consisting of the combination of frictional and spur gears having exactly the same pitch diameter, and means automatically to maintain a driving frictional engagement of the friction surfaces.
11. The combination of a driving element 10 and a driven element, means for transmitting motion from the driving element to the driven element consisting of the combination of friction and spur gears, the friction gear having exactly the same pitch line as the spur gear, the frictional driving surface being parallel to the axis of rotation, and means automatically to maintain driving friction between the friction gears.
12. The combination of a driving element 20 and a driven element, means for transmitting motion from the driving element to the driven element, comprising a driving pinion having a friction surface and a spur gear having the same pitch line as said friction surface, a driven member having a frictional surface and a spur gear connected thereto in engagement and contact with said pinion, and means to obtain a driving friction between the said friction surfaces whereby the power will be transmitted 30 through friction surfaces and the spur gears

and form a means to prevent slipping at the friction surfaces.

13. In combination, a driving element and a driven element, means for transmitting 35 motion from the driving element to the driven element consisting of a plurality of gears, each gear having both a frictional surface and spur gears of exactly the same pitch diameter, means to support the plurality of gears, and means to automatically keep them in frictional driving contact in spite of the wear.

14. The combination of a driving element, a driven element, means for transmitting 45 motion from the driving element to the driven element comprising friction gears, means for automatically holding said gears in frictional running contact, and intermeshing spur gears rigidly connected with 50 the friction gears, means to support each of said gears, the pitch line of each of said spur gears being the same as that of its supporting friction gear.

In testimony whereof, I have signed my 55 name to this specification in the presence of two subscribing witnesses.

AUGUST SUNDH.
